DETERGENT COMPOSITIONS

David W. Clarke, Bellevue, Wash., and David B. Hester, Cincinnati, Ohio, assignors to The Procter & Gamble Company, Cincinnati, Ohio, a corporation of Ohio
No Drawing. Filed Feb. 12, 1959, Ser. No. 792,719

4 Claims. (Cl. 252—116)

This invention relates to detergent compositions. More particularly, this invention relates to detergent compositions which are characterized by the generation of a low volume of suds in use but which possess a high level of heavy-duty cleansing ability comparable to general purpose detergent compositions, and which are further characterized by their ability to resist caking under adverse conditions of temperature and humidity.

Still more particularly, this invention relates to detergent compositions having the above characteristics and which possess a high density.

In certain types of automatic laundering machines currently being marketed and which are structurally identified by a drum which is rotatable about an essentially horizontal axis and which carries internally projecting ribs mounted axially on its cylindrical wall, it has been found that general purpose laundering products characterized by the generation of a high volume of suds in use do not perform satisfactorily. In such drum-type machines which effect cleaning of clothes introduced into the drum by tumbling the clothes with a washing solution, general purpose laundering products including detergent compositions containing anionic synthetic sulfate and sulfonate detergents as the active synthetic detergent ingredient do not give their best cleaning performance because the suds formed at concentrations required for good cleansing tend to cushion the movement of the clothes and diminish agitation to the point where inefficient cleaning results.

Recognition of this problem has resulted in the development of detergent compositions which are based upon nonionic synthetic detergents since such detergents possess cleansing ability with relatively low suds generation. Such nonionic detergent compositions are not, however, equal in washing performance to the heavy-duty anionic synthetic detergent compositions in the cleansing of heavily soiled cotton fabrics even though used in washing concentrations above those customarily employed with general purpose heavy-duty laundering products.

As a consequence, a demand has arisen for detergent compositions which possess superior heavy-duty cleansing power but which are characterized by the generation of only a small amount of suds in use.

Efforts which have recently been made to cope with this specific sudsing and detergency problem have resulted in the proposal of certain mixtures of nonionic compounds and saturated high molecular weight acyl-containing compounds in combination with anionic non-soap synthetics to depress sudsing of the anionic non-soap synthetic while maintaining an available high level of cleaning power. These recent advances have been made the subject of patent application Serial No. 587,505, filed May 28, 1956 (now U.S. Patent 2,954,348, granted September 27, 1960), and assigned by E. A. Schwoepp to the assignee of the present application.

It has been found expedient in the industry, to market synthetic detergent compositions possessing heavy-duty cleaning power in laundering applications which have a high density, i.e. a high weight per unit volume. Such products are within the purview of the above referred to application of E. A. Schwoepp.

It is an object of the present invention to provide improvements in such products.

It is a further object of this invention to provide heavy-duty synthetic detergent compositions of the high den-

2

sity type which are essentially anionic, which have adequate heavy-duty cleansing power coupled with markedly depressed sudsing powder, and which also have improved caking characteristics.

Other objects will be readily apparent from the following detailed description.

Wherever herein the term "high density" is referred to in relation to a detergent composition it is to be understood that a detergent composition having a density in the range from about 0.55 to 0.65 gm./cc. (about 5 ounces per cup) is contemplated. This is in contrast to the more prevalent type of granulated detergent composition in the market, and produced for the most part by spray drying techniques, which normally has a density in the range from about 0.28 to 0.35 gm./cc. (about 2.7 to 3.0 ounces per cup).

The present invention is based upon the observation that in the detergent compositions of the type disclosed in the aforementioned Schwoepp application and which are also characterized by a high density, if a polypropoxy ether of n-butanol is substituted for the nonionic constituent of the compositions, an improvement in the caking characteristics of the composition is obtained. Moreover, this improved caking characteristic is obtained without substantial alteration of the other desirable characteristics of such products, primary among which are the coupling of high cleansing ability with low sudsing power, i.e., generation of only a small volume of suds during use.

The particular constituent contemplated herein as a substitute for the nonionic detergent ingredient of the Schwoepp composition is obtained by condensing about 45 mols of propylene oxide with 1 mol of butyl alcohol, the resulting propylene ether of butyl alcohol having a molecular weight of about 2650, and having a viscosity of about 1905 in Saybolt Universal seconds at 100° F. This product is commercially available under the trade name Ucon Fluid DA 1905 and as a matter of convenience will be referred to hereinafter by its trade name.

Such condensation product, although it has no specific hydrophobic and hydrophilic portions in the molecule as do the nonionic synthetic detergent components of the Schwoepp compositions, when substituted for the nonionic detergent component in such compositions, unexpectedly functions to synergistically coat with the saturated high molecular weight acyl-containing component of those compositions to give the suds depressant effect of the nonionic detergent-high molecular weight acyl-containing component combination. In addition, the Ucon Fluid DA 1905 imparts to the compositions a greater resistance to caking under conditions of temperature and humidity which would normally promote caking in a particulate detergent product.

Thus, the detergent compositions of this invention are characterized by a high density and consist essentially of a water-soluble alkali metal salt of a sulfuric reaction product having in its molecular structure an alkyl radical having from 8 to 18 carbon atoms and a radical selected from the group consisting of sulfonic acid and sulfuric acid ester radicals, the said salt having pronounced sudsing and detergent power in aqueous solution, at least an equal weight of alkali metal polyphosphate, and as a suds depressant and caking inhibiting ingredient a mixture of (1) at least two compounds having acyl radicals of different carbon atom content and selected from the group consisting of saturated fatty acids having from about 14 to about 31 carbon atoms and alkali metal soaps thereof, at least 50% of said compounds containing at least 16 carbon atoms, and (2) a water-insoluble compound comprising the reaction product of propylene oxide with butyl alcohol, the said reaction product having a molecular weight of about 2650 and a viscosity of about 1905 Saybolt Universal seconds at 100° F. (Ucon Fluid DA

1905). This Ucon can be employed in the detergent composition in an amount from about 1% to about 10% by weight thereof, the amount in all cases, however, being sufficient to inhibit caking of the compositions.

The ability of the aforesaid Ucon to inhibit caking is so pronounced that it has been possible to market the high density products, to which this invention is directed, in plain paperboard cartons without concern that the product will cake in the carton if subjected to adverse humidity and temperature conditions. In contrast, if high density products of the type disclosed in the aforementioned application of E. A. Schwoeppe were to reach the consumer in the most desirable and acceptable physical condition, i.e., relatively completely uncaked, it was generally considered that packaging in asphalt impregnated cartons was necessary—the asphalt impregnation giving a degree of water-impermeability to the carton so that the adverse effect which excessive humidity has upon product caking is minimized. This will be more evident from the following specific example in which all parts are by weight.

The ability of the products of the present invention to maintain a desirable free-flowing state even though packaged in untreated cartons results in a significant economic advantage, the cost of the untreated paperboard cartons being substantially less than that of asphalt-impregnated cartons.

Example

Two detergent products having the following high density compositions were prepared.

	Parts by weight		35	Pour grade
	Product A	Product B		
Alkyl benzene sulfonate whose alkyl radical was derived from propylene and averages about 12 carbon atoms	14.0	14.0		
Pluronic L-64-F-68 Mix ¹	2.0	0		
Ucon DA 1905	0	2.0		
Fatty acid ²	2.0	2.0		
Sodium tripolyphosphate	48.0	48.0		
Sodium silicate (ratio of Na ₂ O-SiO ₂ of 1:2)	10.0	10.0		
Sodium sulfate	19.0	19.0		
Water and miscellaneous	5.0	5.0		

¹ Condensation products of ethylene oxide with a hydrophobic base formed by the condensation of propylene oxide with propylene glycol and having molecular weights of approximately 3,000 and 8,000 respectively.

² A commercial mixture of fatty acids derived from hydrogenated fish oil, bearing the brand name Industrene 250, having a constitution within the following range:

	percent	
C ₁₂	0-2	
C ₁₄	do 8-16	
C ₁₅	do 39-49	
C ₁₆	do 25-31	
C ₂₀	do 7-14	
C ₂₂ and higher	do 1-9	
Titer °C.	50-56	
I.V. (maximum)	5	
S.V.	198-215	

The preparations were carried out by first preparing a spray-dried granular composition containing substantially all of the ingredients of the respective compositions above except for the phosphate. These spray-dried granular compositions were then mechanically mixed with the sodium tripolyphosphate in the ratio of 1 part of phosphate to 3 parts of the spray-dried granular composition by weight.

The above products were packaged in cartons which had received no special moistureproofing treatment, i.e., they were not asphalt-impregnated, and were exposed to air at 80° F. and 80% relative humidity. After storage under these conditions for varying lengths of time, as indicated in the table below, the samples were removed from storage, the cartons were opened and the contents poured out by machine to determine the caking grade. The grading scale covered the range from 0 to 10, a grade of 0 representing a product that could not be removed from the carton unless it was torn completely open

5 and a grade of 10 representing a product having the free flowing properties of dry sand. The actual grade given was an arbitrary value representative of the proportion of the total amount of product in the carton which would pour out under controlled and reproducible conditions and pass through a wire screen having a 1/4" mesh. The averaged results obtained from 24 samples of each of the products are shown in the table below.

Month	Pour grade	
	Product A	Product B
1	8.2	10
2	4.0	9.8
3		8.1

20 It is evident from the above comparison that the product of the present invention which contains Ucon DA 1905 is markedly improved in its resistance to caking on exposure to adverse conditions of humidity and temperature.

25 As further evidence of the caking inhibiting effect which is characteristic of the compositions of this invention a detergent product of the approximate composition of sample B in the foregoing example was exposed to humid storage conditions such as are encountered in Florida. Such products were observed to retain their good caking characteristics for up to 6 months as evidenced by the following data.

Months:	Pour grade	
	1	10
3		9.8
6		9.8

30 It is to be appreciated that the proceeding specific example is not to be considered limiting of the present invention and that wide latitude in the choice and amounts of the various constituents of the compositions of this invention can be exercised without loss of the particular benefits of the invention.

35 The anionic synthetic detergent to which reference is made is generally referred to as a water-soluble salt of an organic sulfuric reaction product having in its molecular structure an alkyl radical having from about 8 to about 18 carbon atoms and a radical selected from the group consisting of sulfonic acid and sulfuric acid ester radicals. Important examples of the synthetics which form an active part of the composition of the present invention are the sodium or potassium alkyl sulfates, especially those derived by sulfation of higher alcohols produced by reduction of glycerides of tallow or coconut oil; sodium or potassium alkyl benzene sulfonates, especially those of the type described in U.S. Letters Patent 2,220,099 and 2,477,383 in which the alkyl groups contain from about 9 to about 15 carbon atoms; sodium alkyl glyceryl ether sulfonates, especially those ethers having alkyl groups derived from tallow and coconut oil; sodium coconut oil fatty acid monoglyceride sulfates and sulfonates; sodium salts of sulfuric acid esters of the reaction product of one mole of a higher fatty alcohol (e.g. tallow or coconut oil alcohols) and about 3 moles of ethylene oxide; and others known in the art, a number being specifically set forth in the Byerly U.S. Letters Patent 2,486,921 and Strain U.S. Letters Patent 2,486,922. Such anionic synthetic detergents can be utilized in the compositions of the present invention in amounts from about 4 to about 40% by weight of the composition.

40 The high molecular weight acyl-containing component (fatty acid mixture or soaps thereof) which can be employed in the practice of the present invention include mixtures of at least 3 high molecular weight compounds having acyl radicals of different carbon atom content, at least 50% of the said compounds having at least 16 carbon atoms. The presence of at least 5% of said

compounds having at least 20 carbon atoms will be beneficial.

The presence of other acyl-containing materials in relatively small amounts, such as saturated C₁₂ and C₁₄ acid and unsaturated C₁₈ (oleic and linoleic) fatty acid is not harmful and can even be beneficial, provided the mixture otherwise is constituted of at least 50% saturated acyl-containing components having 16 or more carbon atoms.

Variations in the fatty acid compositions, for example, meeting the above specifications, can fall within the following range of percentages.

	Percent
Myristic acid	0-25
Palmitic acid	0-50
Stearic acid	0-50
Arachidic acid	0-40
Behenic acid	0-40
Lignoceric acid	0-25
Cerotic acid	0-25
Melissic acid	0-25
Oleic acid	0-30
Linoleic acid	0-10

Fatty acid compositions which find value in the practice of the present invention are commercial products known as "Triple Pressed Stearic Acid," which is mainly a mixture of palmitic and stearic acids, "Hyfac 431," and "Hydrofol 51 GG." Bulletins issued by the manufacturers report that the latter two products, which are particularly effective, are mixtures of fatty acids, derived from hydrogenated marine oils. "Hyfac 431," for example, is reported to contain 8% myristic, 29% palmitic, 18% stearic, 26% arachidic, 17% behenic, and 2% oleic acids. Hydrofol 51 GG is reported to contain 7.5% C₁₄ acid, 33.3% C₁₆ acid, 27.2% C₁₈ acid, 17.2% C₂₀ acid and 14.8% C₂₂ acid. The unsaturated acid content of this mixture is said to be about 4.3%. Generally, any related fatty acid mixture having about 5-15% myristic acid, about 25-35% palmitic acid, about 15-30% arachidic acid, and about 10-20% behenic acid is of outstanding utility in the practice of the invention.

As above indicated, the mixture of alkali metal soaps of the fatty acids can be employed as well as the fatty acids or mixtures of fatty acids and soaps. Actually, the normal alkalinity desirable in the heavy-duty detergent compositions contemplated herein is sufficient to convert at least a part of the fatty acid to soap, and in washing solutions of the present detergent compositions the fatty acids can exist in whole or in part as the alkali metal soaps.

The amount of acyl containing component can be varied depending upon the particular characteristics desired in the final composition and upon the amount of Ucon Fluid DA 1905 employed. Usually, the presence from about 1 to 10% of the fatty acid mixture or soap, calculated as fatty acid, and based upon the total product will suffice.

The amount of Ucon Fluid DA 1905 is variable depending upon the ultimate characteristics desired in the final product and also upon the amount of fatty acid mixture employed. Usually from about 1 to 10% of Ucon Fluid DA 1905 based upon the total product weight is sufficient. Alkaline detergent salts such as alkali metal pyrophosphate, tripolyphosphate or other higher polyphosphates, can be used in the compositions of the present invention in amounts from about 30 to 80% by weight of the composition.

In terms of the amount of anionic nonsoap detergent, the alkaline salts or builders may be present in equal or much greater amounts, for instance in amount as much as ten times that of the anionic detergent, or even more, the upper limit of the salt to detergent ratio not being critical.

Many miscellaneous materials including moisture, coloring agents, fluorescent dyes, perfume, carboxymethyl cellulose, sodium carbonate and other alkaline salts as well as various other materials well known as constituents in detergent compositions can also be present.

Having thus described the invention, what is claimed is:

1. A detergent composition possessing heavy-duty cleansing power in laundering applications and characterized by a high density, depressed sudsing action, and resistance to caking which consists essentially of about 4% to about 40% of a water-soluble alkali metal salt of a sulfuric reaction product having in its molecular structure an alkyl radical having from 8 to 18 carbon atoms and a radical selected from the group consisting of sulfonic acid and sulfuric acid ester radicals, the said salt having pronounced sudsing and detergent ability in aqueous solution, at least an equal weight of alkali metal polyphosphate, and, as a suds depressant and caking inhibitor, about 2% to about 20% of a mixture of (1) about 1% to about 10% of at least two compounds having acyl radicals of different carbon atom content and selected from the group consisting of saturated fatty acids having from about 14 to about 31 carbon atoms and water-soluble alkali metal soaps thereof, at least 50% of said compounds containing at least 16 carbon atoms, and (2) a water-insoluble compound comprising the reaction product of about 45 mols of propylene oxide with about 1 mol of butyl alcohol, the said reaction product having a molecular weight of about 2650 and a viscosity of about 1905 Saybolt Universal seconds at 100° F. and being present in the detergent composition in an amount from about 1% to about 10% by weight thereof and sufficient to inhibit caking of the composition.
2. The detergent composition of claim 1 in which the acyl containing component corresponds to a mixture of about 0-2% lauric acid, about 8-16% myristic acid, about 39-49% palmitic acid, about 25-31% stearic acid, about 7-14% arachidic acid and about 1-9% behenic and higher fatty acids.
3. The detergent composition of claim 1 wherein the organic sulfuric reaction product is alkali metal alkyl benzene sulfonate in which the alkyl radical has an average of about 12 carbon atoms.
4. The detergent composition of claim 1 in which the alkali metal polyphosphate is sodium tripolyphosphate.
